UNITED STATES PATENT OFFICE

150,654

DESIGN FOR A TEXTILE FABRIC

Edwin Raphaels, New York, N. Y.

Application November 24, 1947, Serial No. 142,754

Term of patent 7 years

(CL. D92—1)

To all whom it may concern:

Be it known that I, Edwin Raphaels, a citizen of the United States of America, residing in New York, county of New York, and State of New York, have invented a new, original, and ornamental Design for a Textile Fabric, of which the following is a specification, reference being had to the accompanying drawing, forming part thereof.

The figure on the drawing is a view of a textile fabric, showing my new design.

I claim:

The ornamental design for a textile fabric, substantially as shown.

EDWIN RAPHAELS.
